UNITED STATES PATENT OFFICE.

BYERS W. KADEL, OF ROANOKE COUNTY, VIRGINIA.

DRAFT-RIGGING FOR RAILWAY-CARS.

1,228,216.

Specification of Letters Patent. Patented May 29, 1917.

Application filed January 6, 1915. Serial No. 723.

To all whom it may concern:

Be it known that I, BYERS W. KADEL, a citizen of the United States, residing in the county of Roanoke and State of Virginia, 5 have invented certain new and useful Improvements in Draft-Rigging for Railway-Cars, of which the following is a specification.

The present invention pertains to draft 10 gears for railway cars and the principal object thereof is to arrange two draft gears to act in tandem with each other, thereby increasing the total gear capacity. Further objects are to arrange this additional gear 15 capacity so that it will act in buffing only or act to a greater extent in buffing than in pulling. It will be understood that the shock from buffing railway cars is much more severe than that from pulling, hence 20 heretofore if a gear were made of such a capacity as to absorb a large percentage of the buffing load it has been too rigid and unyielding in pulling. With the improvements embodied herein the extra gear capacity 25 may be made to act in the buffing direction only, the regular gear serving as usual in pulling.

With these and other objects in view the invention consists of the arrangement, formation and the combination of elements as herein described and particularly claimed.

In the drawings, Figure 1 is a vertical, longitudinal section of a portion of a car having my invention applied to it and Fig. 35 2 is a partial plan view of the same, certain unrelated parts of the car being removed in order to show the draft parts more clearly. Fig. 3 is a transverse vertical section, taken on the line C D, Fig. 1.

40 Fig. 4 is a broken view similar to Fig. 1, showing a modified form of the invention, and Fig. 5 is a horizontal section taken on the line A B, Fig. 4.

Fig. 6 is a vertical, longitudinal section 45 of a still further modified form of my invention and Fig. 7 a plan view of the same.

Referring now to these drawings, 1 represents the center or draft sills of a car, 2 the cover plate thereon, 3 the end sill of the car, 50 4 the coupler striking plate, 5 the coupler and 6 the coupler carry iron. All of these parts are of the customary approved construction.

The coupler 5 is provided with the cus-

tomary draft abutments 7 and these have 55 operative engagement with draft lugs 8 on the draft members 9 in pulling, the coupler 5 being herein shown as having slideable engagement with the draft members 9 in buffing.

60 The draft members 9 are shown as being integral with and forming frontwardly disposed extensions from a draft gear casing 10 and for a more complete description of this construction, reference should be made to 65 my pending application entitled "Draft rigging for railway cars", the same bearing Serial #874,999, and having been filed December 1, 1914.

70 The casing 10 is tapered from the front toward the back, and disposed within the cavity thereof are the contained and operative parts of the draft gear.

75 The casing 10 is shown as containing two separate friction draft gears, and the one disposed within the rear end thereof is shown substantially as a duplicate of that described in the said pending application, Serial #874,999. It will be understood, however, that other forms of gears might 80 be used, the particular forms being depicted to illustrate the new method of working two draft gears in tandem.

85 The elements of the front gear as shown being somewhat different from the back gear, its structure and operation will now be explained.

90 Abutting the back end of the coupler 5 at 11, or rigidly secured thereto, is a coupler extension 12, the same being adapted to form a strut between the said coupler and the follower plate 13 of the back draft gear. Thus in buffing it will be seen that the coupler load, or a portion thereof will be transmitted directly through this strut to the 95 back draft gear, the same receiving and dissipating it in the customary manner.

100 The strut 12 as shown is cylindrical in form, and disposed within the annular space between this strut and the inside of the casing 10 are wedge shaped friction blocks 13^a, the same having their faces formed to coincide with the external surface of the strut 12 and the tapered internal surface of the casing 10. These blocks 13^a are made in 105 sections surrounding the strut 12 and they are of less length than this strut.

Disposed between the coupler abutments

7 and these blocks 13^a is a spring 14, the washer 15 serving to give uniform bearing to the end of the spring 14.

In buffing it will now be seen that when the coupler 5 moves backward within the casing 10 or the draft members 9, the washer 15 is carried with it and the spring 14 is compressed between this washer and the friction blocks 13^a; the converging cavity 10 of the casing 10 causing these blocks to wedge against the strut 12. At the same time the strut 12 is being pushed back by the coupler, and the pressure of blocks 13^a bearing forcibly thereon, produces friction 15 between the moving surfaces and dissipates a large portion of the coupler blow before it reaches the regular or back draft gear.

In pulling, the abutments 7 on the coupler engage the draft lugs 8 on the draft members 9, (in this case integral with the casing 10), and the casing 10 is pulled forward, the back gear being compressed against the follower 13, which has been arrested in its frontward movement by the stops 16 on the draft sills 1, this action being the usual means employed in draft mechanisms. In this frontward or pulling movement the casing 10 and the strut 12 move together, (without movement relative to each other), 25 consequently, there is now no friction between the blocks 13^a and the strut 12. The spring 14, however, is held from frontward movement by the arrest of the washer 15 against the key 17, so that the front gear is 30 a simple spring gear in pulling.

It will thus be seen that with the parts so arranged I have provided a friction draft gear that operates as a friction gear in both pulling and in buffing and in connection therewith a second or independent draft gear that functions as a friction gear in tandem with the first gear in buffing and functions as a spring gear in tandem with the first gear in pulling: Hereinafter it will 40 be shown, that with very slight modifications this second gear may be made to go out of service entirely in pulling.

The key 17 passes loosely through the elongated slot 18 in the coupler 5 and the strut 12 so that they have slidable engagement with the said key in both pulling and buffing. The key is held from movement by means of the brackets 19 which are secured to the draft sills 1 and through which the 50 key 17 passes. These brackets serve also as spacers to maintain the alinement of the draft rigging between the draft sills.

As previously stated, the draft members 9 are shown as integral with the casing 10, 55 and for this particular form of front gear the casing may extend as a complete hollow cylinder to the front of the draft lugs 8. In the front end of this full length casing is an oblong opening 20 extending substantially 60 the full width of the cavity of the casing

in the transverse direction but less than this width vertically, the resulting walls at the top and bottom forming the draft lugs 8. The various working parts of the front or rear draft gear may be entered through this 70 opening. The washer 15 is provided with spaced ears or extensions 21 at each side and these accommodate the key 17 between them.

The last of the internal parts to be entered through the opening 20 is this washer 7 15, and after being entered it is given a quarter turn so as to bring the ears 21 above and below the opening 20, or just back of the draft lugs 8. The coupler 5 is then given a quarter turn so as to bring the abutments 7 into registry with the longer, transverse direction of the opening 20, and the coupler is then pushed back through the opening 20, the ears 21 on the washer 15 positioning on each side of the narrow way 8 of the coupler. The coupler, and consequently the washer 15 with it, are now returned the one quarter turn, bringing these parts into the positions shown in the drawings, and the key 17 is then entered through the brackets 19 and the slot 18, holding the parts from undesired turning. The ears 21 on the washer 15 now serve as lateral spacers for the coupler within the casing 10.

It will be seen that by this method of forming the draft members the metal at either side of the coupler, at 22 and 23, forms a vertical wall or tie between the draft members 9 and the draft lugs 8, and the draft members are thereby held from springing apart in pulling. At the same time the coupler has sliding engagement with the draft members in buffing.

This draft mechanism may also be used without the key 17, as I have shown in Figs. 4 and 5, in which figures I have illustrated also the use of a coupler having the standard Master Car Builders' butt end 24, and having the strut 12 made in a separate piece from the coupler. When so used without the key 17 it will be seen that all of the parts function the same in buffing as in the mechanism shown in Figs. 1—2 and 3, but in pulling, there now being nothing to arrest the frontward movement of the washer 15, the spring 14 is not compressed, hence the rear gear only acts in pulling while both gears act in buffing. The advantage of this will be evident to those acquainted with the art, as the heavy blows occur in buffing, while the pulling requires much less gear capacity to dissipate and absorb it, and at the same time such a heavy gear capacity is undesirable in starting a long train.

Furthermore, it should be noted that double travel is not required to effect this extra gear capacity as the strut 12 conveys only the unabsorbed portion of the coupler load to the back gear in buffing. Hence the use of these two independent and peculiarly

connected draft gears gives a high capacity gear of relatively short travel in buffing and a more yielding gear with the same relatively short travel in pulling, thereby avoiding undue slack in the train.

In the absence of the key 17 as a support for the various parts, the carry iron 25 is provided. And in the absence of this key as a means for holding the spacers 21, the bolt 26 is applied, the spacers 27 being inserted at each side of the coupler and the bolt 26 holding them in place.

The essential elements of my invention might be embodied in various forms, as for instance, in Figs. 6 and 7, I have shown how the strut 12 may be used with a draft gear having the draft yoke 28 rigidly attached to the coupler. In this embodiment the rear gear functions as in customary practice, between the stops 29 and 30 on the draft sills. The strut 12 is in this instance made tapered and as it moves backward the blocks 31 are expanded against the casing 32, the backward movement of the blocks being resisted by the spring 33 and the backward movement of the casing being arrested by the stops 29, these serving also, as already stated, for the back draft gear in pulling. Thus it will be seen that various alterations might be made in my invention within the scope of the claims without departing from the spirit thereof.

Having thus described my invention, what I claim is:

35 1. In a draft rigging for railway cars, a coupler, a casing slidably connected thereto, frictional elements within the casing and co-operating therewith to frictionally resist movement of the said coupler under both buffing and draft, and further friction elements and a spring within the said casing said last mentioned elements coacting with the said casing to frictionally resist movement of the coupler in one direction only.

2. In a draft rigging for railway cars, a 45 coupler, a draft gear disposed behind said coupler, a strut interposed between the said coupler and the said draft gear, said strut being movable by said coupler under both buffing and pulling, the said coupler having 50 operative engagement with the said draft gear through the said strut in buffing and independent of the said strut in pulling, and additional friction means in co-operative engagement with the said strut in buffing. 55

3. In a draft rigging for railway cars, a coupler, a draft gear disposed behind said coupler, a strut interposed between the said coupler and the said draft gear, said strut contacting with the said coupler and being 60 movable therewith in both directions, the said coupler having operative engagement with the said draft gear through the said strut in buffing and independent of the said strut in pulling, and an additional draft 65 gear in operative engagement as a spring draft gear with the said strut in pulling.

4. In a draft rigging for railway cars, a coupler, a draft gear disposed behind the said coupler and in operative engagement 70 therewith, said draft gear comprising a hollow casing, a rearward extension from the said coupler disposed within the said casing and having movement relative thereto in buffing, said movement being equal to the 75 travel of the coupler, friction elements engaging the said coupler extension and the said casing, and a spring adapted to co-act with the said friction elements to wedge the same between the said coupler extension and the said casing. 80

In testimony whereof I affix my signature in presence of two witnesses.
